[57] CLAIM

The ornamental design for a coffee filter separating utensil, substantially as shown and described.

DESCRIPTION

FIG. 1 is a perspective view of a coffee filter separating utensil showing my new design;

FIG. 2 is a top plan view thereof;

FIG. 3 is a bottom view thereof;

FIG. 4 is a front elevational view thereof the opposite side being a mirror image;

FIG. 5 is a fragmentary sectional view of FIG. 4 taken along line 5—5; and

FIG. 6 is a flattened development view of the bottom arcuate surface thereof taken in the direction of the arrows 6—6.
